*Primary Examiner — Mehri F Bajoul**(74) Attorney, Agent, or Firm — Paratus Law Group, PLLC*(57) **CLAIM**

The ornamental design for a cover for electronic device, as shown and described.

DESCRIPTION

FIG. 1 is a perspective view of front, bottom and right side of a cover for electronic device showing my new design; FIG. 2 is a perspective view of front, bottom and left side thereof;

FIG. 3 is a perspective view of rear, top and left side thereof; FIG. 4 is a perspective view of rear, bottom and left side thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof; and,

FIG. 11 is a perspective view thereof, showing the claimed design in condition of use.

The broken lines on the cover for electronic device depict portions that form no part of the claimed design. The broken lines showing the electronic device, in FIG. 11, illustrate environmental structure that form no part of the claimed design.

1 Claim, 7 Drawing Sheets---
